UNITED STATES PATENT OFFICE.

FRIEDRICK GOETSCH, OF BLOOMINGTON, ILLINOIS.

IMPROVEMENT IN MEDICAL COMPOUNDS.

Specification forming part of Letters Patent No. 125,286, dated April 2, 1872.

To all whom it may concern:

Be it known that I, Dr. FRIEDRICK GOETSCH, of Bloomington, in the county of McLean and in the State of Illinois, have invented a certain new and useful Medical Compound; and do hereby declare that the following is a full, clear, and exact description thereof.

My compound consists of the following ingredients, in about the following proportions: Aloes, four ounces; Spanish saffron, one ounce; German theriac, two ounces; rhubarb, two ounces; myrrh, three ounces; bole Armenia, one and one-half ounce; angelica, two ounces; arom. sulph. acid, one-half ounce; spirit salts, one-half ounce; gentian, three ounces; dittany, three ounces; tormentilla, two ounces; camphor, one-half ounce; zedoari, two ounces; agaric, one ounce; castoreum, one-half ounce; elecampane, one ounce; pimpinella, two ounces; distlis, two ounces; chamædrys, three ounces; French cogniac, two pounds.

I do not wish to confine myself to the precise proportions of the ingredients herein men-

tioned, as I may vary the same to suit circumstances.

This medicine is an unfailing remedy for the following diseases: Cholera, epilepsy, fever- and -ague, hemorrhoidal complaints. It strengthens the memory, improves the eyesight, gives tone to the stomach, cures inveterate headaches, and invigorates all nerves of the body. It is a preventive from all contagious diseases, and is an effective means to remove any cold.

Having thus fully described my invention, what I claim as new, and desire to secure by Letters Patent, is—

The within-described medical compound, consisting substantially of the ingredients herein set forth.

In testimony that I claim the foregoing I have hereunto set my hand this 31st day of January, 1872.

FRIEDRICK GOETSCH.

Witnesses:

THOS. SLADE,
AUGUST PAPENDICH.
